UNITED STATES PATENT OFFICE

128,513

DESIGN FOR A GASOLINE CAN

William W. Wittie, Chicago, Ill.

Application November 28, 1940, Serial No. 96,907

Term of patent 7 years

To all whom it may concern:

Be it known that I, William W. Wittie, a citizen of the United States, residing at Chicago, in the county of Cook and State of Illinois, have invented a new, original, and ornamental Design for Gasoline Cans, of which the following is a specification, reference being had to the accompanying drawing, forming part thereof.

Fig. 1 is a perspective view of a gasoline can

looking from one side showing my new design;

Fig. 2 is a perspective view looking from the front and

Fig. 3 is a rear elevational view.

I claim:

The ornamental design for a gasoline can, as shown.

WILLIAM W. WITTIE.
